UNITED STATES PATENT OFFICE.

HARRY R. ATWATER, OF CLEVELAND, OHIO, ASSIGNOR TO THE OSBORN MANUFACTURING COMPANY, OF CLEVELAND, OHIO, A CORPORATION OF OHIO.

MOLD-MAKING MACHINE.

1,070,316.

Specification of Letters Patent. Patented Aug. 12, 1913.

Application filed May 19, 1910. Serial No. 562,165.

To all whom it may concern:

Be it known that I, HARRY R. ATWATER, a citizen of the United States, and a resident of Cleveland, county of Cuyahoga, and State of Ohio, have invented a new and useful Improvement in Mold-Making Machines, of which the following is a specification, the principle of the invention being herein explained and the best mode in which I have 10 contemplated applying that principle, so as to distinguish it from other inventions.

My present invention, relating as indicated to mold making machines has more particular regard to rock-over machines of the type illustrated in U. S. Letters Patent No. 890,919, dated June 16, 1908. The rock-over type of machine, as need scarcely be explained, is characterized by having separate parting and filling stands located adjacent to each other with a holder for the pattern plate pivotally secured to said filling stand so as to be adapted to be swung over in reverse position onto the parting stand. The latter is vertically reciprocable so that when 25 the holder proper is thus reversed, such holder being then sustained by the filling stand in horizontal position, the mold may be drawn away from said holder and the pattern plate secured thereto. The patented 30 structure just referred to is further characterized by having the parting stand so constructed as to be adapted to support the mold in unchanged position, while it is being freed from the pattern. Such means in the 35 specific form there illustrated comprise a plurality of laterally spaced depressible members that project upwardly from the parting stand and means for locking said members in whatever position they are 40 forced to assume after the mold has been rocked over into position for parting. Such mold will thus be sustained, when it is lowered from the pattern, in exactly the position assumed by it when first turned over.

45 The present invention has as its more especial object then, the provision of improved means for locking such depressible members, whereby all may be locked simultaneously and by a single operation.

50 To the accomplishment of these and related objects, the invention consists of the means hereinafter fully described and particularly pointed out in the claims.

55 The annexed drawings and the following description set forth in detail certain mecha-

nism embodying the invention, such disclosed means constituting, however, but one of various mechanical forms in which the principle of the invention may be used.

In said annexed drawings: Figure 1 is a 60 side elevation of a mold making machine embodying my several improvements; Fig. 2 is a top plan view of the parting stand of such machine; Fig. 3 is similarly a bottom plan view of the same with certain accessory 65 parts; Fig. 4 is a vertical sectional view taken on the line 4-4, Figs. 2 and 3; and Fig. 5 is a sectional detail.

The frame of the machine consists in the case in hand of the usual mold filling and 70 parting stands A, A' and for convenience of movement is mounted on low wheels or rollers. Such filling stand, which is designed to receive the mold B, pending the filling and tamping of the sand therein, consists simply of a plunger a with a rest or head a' on its upper end, said plunger being 75 adjustably secured in the frame of the machine, but when in use being retained at a predetermined elevation. The parting stand 80 A', on the other hand, comprises a plunger, or rather two plungers, c adapted to be vertically reciprocated by means of a rock-shaft a² that bears cams a¹ engaging with the lower end of the plungers. The latter are 85 provided with a platform-like head C which supports the mold bottom b in the final stage of the machine's operation, although such mold does not directly contact with said platform, as will presently be explained. 90 Intermediate between the two stands just described, are two laterally spaced standards A² that are integral or rigid with the frame of the machine, and serve to oscillatorily 95 support the pattern plate holder B'.

The details of construction of such stands and holder need not here be noted, as they form no part of the present invention, and are, moreover, fully described and claimed in my issued Patent No. 937,036, 100 Oct. 19, 1909.

The general operation of the machine will require but little further description in addition to what has already been given. As illustrated in Fig. 1, the pattern plate holder 105 B' with a mold B attached thereto is shown in reverse position just preparatory to the stripping of the mold from the pattern. Its position (without a mold attached) on the filling stand is indicated in dotted outline. 110

It is when positioned over the parting stand that adjustment of the top of the latter to the under side of the mold is necessary, and to this end, a series of four vertically reciprocable pins or plungers c' are provided in said parting stand top, one at each corner. Said pins correspond in general with those illustrated in the first of the above named patents, being held in suitable pockets c^2 in which are provided compression springs c^3 , one beneath each plunger to normally retain the same in elevated position until the weight of the rocked over mold depresses or forces it down. (See Fig. 5 for details). In order, however, to lock the pins in this depressed position, I provide, instead of the individual cams of the prior structure, two similarly curved, oppositely disposed locking bars C' of the general form clearly shown in Fig. 3. Each such bar, in other words, resembles a flattened U, its outer ends c^4 having a sufficient spread to respectively enter apertures c^5 in the sides of the pockets that receive the corresponding pair of reciprocable plungers c' . Such ends are, moreover, concave to conform with the cross-section of the pins and be capable of having corresponding increased frictional contact therewith. The central portions of the locking-bars extend inwardly substantially to the center of the platform of the parting stand. Rotatably mounted, however, intermediately between such inner portions of the bars is a rotatable cam member C^2 having a pair of oppositely disposed similar cam faces c^6 , which, upon rotation of such member, respectively engage said locking bars to force the same outwardly and thus cause their extremities to press against the pins. Said cam member is also provided with a flange c^7 upon which the inner portions of the bars may loosely rest, no other support being required in addition to this and that afforded by apertures c^5 . Integral with the cam is a short shaft c^8 , which extends upwardly through a suitable aperture c^9 in the platform C to receive an operating lever c^{10} , the outer end of which, forming a handle, lies clear of the platform in convenient reach of the operator. Such shaft, or in other words, the cam member is not fitted tightly in the bearing formed by aperture c^9 but is allowed a certain amount of lateral floating or play, the object of which is to permit of an equalization of the outward pressure exerted upon the locking bars. Each bar, of course, is by its construction adapted to distribute the pressure it receives equally between the two pins whereby it engages. There is also a certain amount of spring in said bars, so that when the cam is rotated into locking position, it will remain there and at the same time proper pressure be applied to the pins, or plungers, to securely hold them under the

weight of the mold after the latter is freed from the pattern plate holder.

As in the case of the prior parting stand structure upon which this invention is an improvement, so here there is no necessary limitation to the use of such stand in a molding machine of the rock-over type, since it is equally adaptable to use in roll-over and other forms of machine. In all such constructions where the adjustable plungers or pins may be used, it will be an obvious advantage not only in point of time and convenience, but also in the matter of security, to have such pins secured simultaneously and from a common operating handle; for with the previous arrangement of separate cams for locking the individual pins there is always danger that one may be released or slip and thus endanger the mold.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a mold-making machine, a plurality of independently adjustable members each adapted to contact with the mold at one of a series of laterally spaced points, preparatory to freeing said mold from a pattern embedded in the material with which the flask of the mold is rammed; and simultaneously operative means adapted to retain said adjustable members in such contacting position, said means including members frictionally engaging against said adjustable members.

2. In a mold-making machine, a plurality of independently adjustable members each adapted to contact with the mold at one of a series of laterally spaced points, preparatory to freeing said mold from a pattern embedded in the material with which the flask of the mold is rammed; and simultaneously operative members adapted frictionally to engage said adjustable members transversely of their path of adjustment.

3. In a mold-making machine, laterally spaced vertical pins arranged to be depressed by the mold-bottom during the placing of a mold in position preparatory to freeing the mold from a pattern embedded in the material with which the flask of the mold is rammed; means acting to retain the pins in their upper and normal position; and simultaneously operative means for retaining said pins from depression further than by said mold-bottom.

4. In a mold-making machine, the combination of a stand; laterally spaced depressible members mounted therein and arranged to contact with the mold-bottom upon a

mold being placed in position preparatory to freeing the same from a pattern embedded in the material with which the flask of the mold is rammed; locking members movable transversely of said depressible members to retain the latter in such contacting position; and means adapted to simultaneously actuate said locking members.

5. In a mold-making machine, the combination of a stand; laterally spaced depressible members mounted therein and arranged to contact with the mold-bottom upon a mold being placed in position preparatory to freeing the same from a pattern embedded in the material with which the flask of the mold is rammed; means acting to retain said depressible members in their upper and normal positions; locking members movable transversely of said depressible 15 members to engage and retain the latter from depression further than by said mold bottom; and means adapted to simultaneously actuate said locking members.

6. In a mold-making machine, the combination of a stand; laterally spaced depressible members mounted therein and arranged to contact with the mold-bottom upon a mold being placed in position preparatory to freeing the same from a pattern embedded in the material with which the flask of the mold is rammed; springs arranged under said depressible members and acting to retain the latter in their upper and normal position; locking members movable 30 transversely of said depressible members to engage and retain the latter from depression further than by said mold-bottom; and means adapted to simultaneously actuate said locking members.

40 7. In a mold-making machine, the combination of a stand; laterally spaced depressible members mounted therein and arranged to contact with the mold-bottom upon a mold being placed in position preparatory to freeing the same from a pattern embedded in the material with which the flask of the mold is rammed; locking members movable transversely of said depressible members to press against the latter and thus 45 retain the same in such contacting position; and means for simultaneously actuating said locking members, said means being adapted to equalize the pressure exerted by the several locking members.

55 8. In a mold-making machine, the combination of a stand; a plurality of pairs of depressible members mounted in said stand and arranged to contact with the mold-bottom upon a mold being placed in position preparatory to freeing the same from a pattern embedded in the material with which the flask of the mold is rammed; two similarly curved locking bars arranged with their central portions directed inwardly and 60 with their outer ends adjacent to corre-

sponding pairs of said depressible members; and means located between the central portions of said bars adapted to simultaneously force the same outwardly and thus cause their ends to bear against said depressible members.

9. In a mold-making machine, the combination of a stand; a plurality of pairs of depressible members mounted in said stand and arranged to contact with the mold-bottom upon a mold being placed in position preparatory to freeing the same from a pattern embedded in the material with which the flask of the mold is rammed; two similarly curved locking bars arranged with their central portions directed inwardly and with their outer ends adjacent to corresponding pairs of said depressible members; and a cam member movably mounted between the central portions of said bars and adapted, upon movement, to simultaneously force the same outwardly and thus cause their ends to bear against said depressible members.

10. In a mold-making machine, the combination of a stand; a plurality of pairs of depressible members mounted in said stand and arranged to contact with the mold-bottom upon a mold being placed in position preparatory to freeing the same from a pattern embedded in the material with which the flask of the mold is rammed; two similarly curved locking bars arranged with their central portions directed inwardly and with their outer ends adjacent to corresponding pairs of said depressible members; and a cam member rotatably mounted between the central portions of said bars and adapted, upon rotation, to simultaneously force the same outwardly and thus cause their ends to bear against said depressible members.

11. In a mold-making machine, the combination of a stand; a plurality of pairs of depressible members mounted in said stand and arranged to contact with the mold-bottom upon a mold being placed in position preparatory to freeing the same from a pattern embedded in the material with which the flask of the mold is rammed; two similarly curved locking bars arranged with their central portions directed inwardly and with their outer ends adjacent to corresponding pairs of said depressible members; and a cam member rotatably mounted between the central portions of said bars and adapted, upon rotation, to simultaneously force the same outwardly and thus cause their ends to bear against said depressible members, said cam member having sufficient lateral play to permit the pressure exerted by said bars to be equalized.

12. In a mold-making machine, the combination of a stand provided with pockets; a plurality of pairs of independently de-

pressible members mounted in such pockets; springs arranged under said depressible members and acting to retain the latter in their upper and normal positions; two similarly curved locking bars arranged with their central portions directed inwardly and with their outer ends adjacent to the corresponding pairs of said depressible members, the walls of the pockets for said members being apertured to receive and sustain such ends; and a cam member rotatably mounted between the central portions of said bars

and adapted, upon rotation, to simultaneously force the same outwardly and thus cause their ends to bear against said depressible members, said cam member being formed with a flange adapted to form a rest for the central portions of said bars. 15

Signed by me this 17th day of May, 1910.
